SPEED AND POWER GEARED HAND WRENCH

Lawrence S. Schneppel and Everett C. Spear,
Cochituate, Mass.

Application May 27, 1948, Serial No. 29,448

4 Claims. (Cl. 74—801)

1

The present invention relates to hand tools of the wrench class and more particularly geared manual wrenches. It aims to provide a universal tool of the stated class, of compact, rugged and otherwise improved construction and arrangement and which by mere reversal of position serves the dual purposes of speed and of power applications, that is, this wrench type of hand tool is adapted to deliver the manual rotative effort selectively at increased speed or at increased power.

In the drawings illustrating by way of example certain embodiments of the invention:

Fig. 1 is an elevation of one form of the tool;

Figs. 2 and 3, upon a larger scale, are respectively axial and transverse sections through the head or main assembly of the tool of Fig. 1;

Fig. 4 is a perspective view of the central drive assembly; and

Fig. 5 shows an embodiment with removable and interchangeable handle means.

The geared wrench of the invention affords the advantages of gearing between the input and the take-off elements yet in a practical and convenient hand-tool form. It is adapted for embodiment in sizes and designs making it universally useful, especially in restricted areas such as frequently encountered for example in the automotive and air-craft industries and wherever parts to be operated on may be difficult for access.

Our novel hand tool or tool accessory comprises three main externally accessible elements. These comprise a pair of opposed and axially aligned relatively rotatable shaft elements either of which is selectively available in three-fold manner, as the driver, the driven or the holding part. The third element is a concentric outer annular member disposed between the opposite ends of the pair mentioned and provided with handle means for alternatively holding it stationary or turning it. Under operation with the aligned shaft elements employed as the driving and driven parts the outer element is held stationary. The off-take result is either increased speed or increased power depending merely on one or the reverse positioning of the tool relative to the work. At other times either one of the aligned shaft pair may be made the stationary member, by holding it fast in any convenient manner, whereupon the rotative effort may be taken off at the opposite non-held shaft member of the pair, by turning the outer circumferential element. Again in this latter manner of use, depending merely on which of the aligned pair is selected for holding and which for take-off, the resulting effort obtained, in this instance through manual rotation of the central outer member, will be either a power application or an increased speed application; that is, selection of one or the other shaft for use as input and output or take

2

off elements respectively determines whether the output is at increased power or at increased speed; in other words, the rotative effort available at one end of the tool will be at higher speed and at less power than available by merely reversing the tool end for end and using the other end, opposite to the first mentioned end, as the output element. Thus the simplified and compact tool of the invention is universally available either for power or for speed requirements and in different combinations as to driver, driven and holder parts as may be most convenient for the particular job and space conditions encountered.

Referring to the drawings in more detail and noting particularly Figs. 2 and 4, the tool comprises a stub shaft 6 and a second generally similar and axially aligned stub shaft 7. The outer ends of these shafts are formed with any preferred tool-engaging formation either male or female and illustrated by way of example as non-round heads 8 and 9, shown as squared. As noted these may be either in the nature of studs or of sockets and may be of the opposite type at the respective ends. The stud form illustrated is generally preferred, as more universally suitable, being conformable to various commercial socket-wrench sets, and being readily convertible to the opposite type of attachment by a socket adapter.

One of the shafts 6, that at the top in Fig. 2, constitutes a connective mount for the intermediate planetary gearing illustrated. Accordingly it is formed, preferably integrally, with a radial disc or retainer plate 10. This plate is drilled at a plurality of equally circumferentially spaced locations to receive in fixed relation a like plurality of pins. In the example shown four such pins 11, 12, 13, 14 are symmetrically distributed about the axis of the shaft 6. The opposite ends of these pins 11—14 are fixed in a like number of similarly arranged seats in a second retainer and spacer plate 15 of like size as the first plate 10.

Journalled on and by the respective pins 11 to 14 is the cluster of intermediary pinions 16, 17, 18, 19. The gear-bearing pins 11—14 are herein fixed in the opposed retainer plates 10, 15 in any suitable manner as by counter-sinking and heading over. The retainer plate 15, in the lower position in Figs. 2 and 4, is centrally recessed for free passage of the adjacent stub shaft 7. The inner portion of said shaft 7 has integrally or otherwise fixed on it a concentric central gear 20 meshing with the series or cluster of pinions 16—19. This central or sun gear 20 and its shaft 7 are proportioned and arranged for reception of the gear 20 between the opposed inner faces of the retainer plates 10 and 15 in end-thrust bearing relation thereto. For further piloting and axial rectification one of the

shafts, herein the upper shaft 6, has an axial end recess 6' while the opposite and relatively rotatable shaft, herein the part 7, has bearing reception in said recess by means of an axially projecting guide stud 7'.

Noting particularly Fig. 4, it will be evident that the parts described to this point, including the shaft pair, the spaced plates and the interposed planetary gearing constitute an operational unit or assembly.

The operating parts further comprise the longitudinally central outer casing and body element 30 which also constitutes the carrier for an internal ring gear 32. This outer annular element 30, 32 preferably is formed integrally as a single piece having the gear teeth 32 at its inner circumferential face. The teeth of this internal gear 32 are adapted to mesh with the planetary cluster of pinions 16 to 19 at the 90° spaced locations herein illustrated. The internal gear teeth 32 are of a length or height approximating that of the other gears, so as to be received with close tolerance between the adjacent margins of the opposed inner faces of the retainer plates 10, 15. Thus the internal gear teeth afford additional guiding and spacing means for the plates peripherally of the latter. It will be noted that the retainer plates 10, 15 have a diameter slightly greater than the root diameter of the annular internal gear or rack 32 and that the edge faces of the plates seat in bearing relation to shoulders 33, 34 on the gear-carrier 30. Accordingly the entire assembly including the outer element 30-32 is mechanically held together independently of any further outside case or bearing means and is capable of functioning in the absence of any further part.

For additional strength, dirt exclusion and like purposes, the tool desirably is finished with opposed circular end pieces or housing covers 36, 37. These comprise centrally bored flanged or disc-like bodies surrounding the respective axially opposed shafts 6 and 7 in bearing relation thereto. The peripheral portions of these end covers and bearers 36, 37 are received by annular seats 38, 39, therefor at the inner faces of the opposed outside rims of the gear-carrier element 30, and are there held as by swaging. Desirably these end enclosures 36, 37 are each formed with an annular recess on the inner wall as for example at 40, 41 adapted to confine packing or sealing means for excluding dirt and retaining lubricant within the tool, such for example as a neoprene washer or packing.

In the modification of Fig. 5, the annular body part 30a of the wrench is formed with a receiving formation as at 53, illustrated as a squared stud for detachable association with a handle or bar 50a having a grip 51a. As shown this demountable bar may be generally similar to the handle element or "strong arm" supplied with ordinary socket wrench sets, including a socket piece 54 pivotally connected to the hand bar 50a as at 55. The reverse arrangement as to socket and stud may be employed, either the male or the female element being on the wrench body 30a and the other element on the handle 50a.

From the foregoing description in connection with the drawings it will be apparent that our geared wrench or wrench accessory is conveniently available as a universal tool for the application of turning effort for the dual purpose of affording either an increase of rotative speed or an increase of rotative power at the given speed. Further, either of these dual speed and

power applications are available in different ways as best suited to the available space limitations at the particular job. Either of the protruding shafts 6 and 7 may be used as the output or driven member, the input power or turning effort being applied either to the opposite shaft 7 or 6 with the radial handle 50 held stationary or to the radial handle 50 with said other shaft 7 or 6 held. It will be understood that in any such uses one of the shafts 6 or 7 is applied to the work while the other shaft 7 or 6 receives any suitable engaging tool or handle such for example as that of an ordinary socket-wrench with or without ratcheting provision. Thus the handle such as 50 of Fig. 1 and 50a of Fig. 5 may be used as an anchor, the rotative input or work effort being applied to the appropriate drive 6 or 7 for the purpose required, with resultant rotative output at the opposite member 7 or 6 in the same direction of turning. Alternatively one drive 6 or 7 may be held by any convenient tool attachment as above mentioned while the radial handle 50 or 50a is turned to afford the desired rotative effort either as a speed increase or as a power increase, depending merely on which of the shafts is held and which is used for the output; in the instance of shaft 6 being held the direction of rotation at the then output shaft 7 is reverse to that of the input at the handle 50. In all other cases the rotative direction of output is the same as that of the input. In any instance a shift from speed to power application or the reverse is instantly possible by simply inverting the position of the wrench head. As indicated on Fig. 1 the respective ends or sides of the wrench head may be distinctively designated in any preferred manner such as the notations "Speed" and "Power". It is further noted that the geared hand tool of our invention affords a choice of three different input to output ratios. In the particular embodiment illustrated by way of example the gearing arrangement is such that use of the two shafts as input and output elements while the head is held against turning affords a ratio of 4 to 1 or 1 to 4 depending on which shaft is used for input and which for output. If the shaft 7 to which the central gear is affixed is held from turning and the rotative effort is applied to the head as by means of the handle 50, the output at the other shaft 6 is in the ratio of 4 to 3. Again, if reversely the shaft 6 is held from turning, rotation of the head as by the handle 50 provides a rotative output at the other shaft 7, in this instance in reverse direction, in the ratio of 3 to 1.

By reason of the compactness, mechanical simplicity and rugged structure of our wrench it is adapted for use in restricted areas where ordinarily only the conventional small non-geared hand tool can have access. Our geared wrench brings to such uses the added important advantage of appropriate power or speed for the given job.

Accordingly the speed and power geared hand wrench of our invention is particularly useful in the automotive and air-craft industries at the numerous work locations where the use of power tools or speed wrenches has heretofore generally been restricted to mechanical parts which are exposed in a readily accessible position.

Our invention is not limited to the particular embodiments thereof illustrated and described herein, and we set forth its scope in our following claims.

We claim:

1. As a new article of manufacture in the hand tool class, a geared head and handle unit particularly for use accessory to stud-and-socket-type hand wrench equipment for manually applying torque selectively at increased power or at increased speed, said unit comprising first and second symmetrical stub shafts relatively rotatable in axial line, the inner shaft ends having mutual bearing support and the outer ends terminating directly in integral socket-wrench-type engaging formations, the first shaft having at the inner end and fixed therewith a coaxial radial flange, the second shaft having freely disposed about an inner portion a radial plate of like diameter as said flange and axially spaced therefrom, a heavy-duty central gear between and in end-bearing relation to the flange and the plate and fixed on the second shaft, a cluster of similar heavy-duty pinions symmetrically spaced around and meshing with the central gear and also in end-bearing relation to and between the flange and the plate, a bearing pin for each pinion spanning between and firmly held at the opposite ends in the flange and the plate respectively, and an internally toothed laterally open ring gear surrounding and meshing with the pinion cluster, the ring gear teeth disposed between the flange and the plate in axial spacing and guide bearing relation thereto at the tooth end faces, and the ring gear having a collar-like outer wall symmetrically encompassing the peripheries of the flange and the plate in relatively rotative bearing and guiding relation thereto and provided externally with radial handle means for holding and for turning it alternatively.

2. As a new article of manufacture, a manual socket-wrench accessory tool constituting a geared handle and wrench element for modifying manual wrench-applied torque, said tool comprising an outer ring element constituting of itself a supporting head having an internal toothed gear medial of the inner wall and having at the respective end faces of the gear teeth laterally open circumferential recesses of a diameter exceeding the tooth root diameter, a pair of axially aligned relatively rotative shafts oppositely extending centrally of the head in mutual supportive bearing relation at the inner ends and having the outer ends exposed and shaped for direct socket-wrench type engagement alternatively with the work and with a handle, each selectively as a driver, as a driven element and as an element to be held, a central gear coaxially within and radially spaced from the internal gear and fast on one of the shafts, a gear cluster unitarily revolvably carried with the other shaft with capacity for individual rotation of the cluster gears, axially spaced plate means angularly fixed with respect to said other shaft for so rotatably mounting the cluster gears in conjoint meshing relation with the internal gear and the central gear, said plate means received and guided circumferentially in the laterally open recesses of the head, and bar handle means extending radially from the outer wall of the head for holding and for turning it accordingly as the shafts are selected for mutual driver and driven relation or for mutual held and driven relation, mere reversal of the tool by 180° turning about the handle axis effecting selection as between speed increasing and power increasing applications.

3. As a new article of manufacture, a geared

wrench handle unit accessory to standard wrench equipment of the stud and socket type, for application of rotary effort selectively at increased speed or at increased power, said handle unit comprising a circular head defined by an outer annulus constituting both a casing and a movable working part having an internal ring gear fixed at the inner wall thereof, a pair of axially aligned relatively rotatable shafts disposed concentrically in and projecting oppositely from the head with standard wrench-type engaging formations at the projecting ends for engagement selectively with a work connector and with a tool for holding and for turning at the user's option, one shaft having at the inner end a radial flange rotatably disposed in the head in flatwise lapped relation to the adjacent end faces of the ring gear teeth, a plurality of equally angularly spaced bearing pins paralleling the shaft axis and mounted at one end in said flange, a bearer plate for the other ends of the pins disposed in the head in similar manner as said radial flange but at the opposite ends of the ring gear teeth, said bearer plate having a central bearing aperture for the adjacent shaft, a central gear fixed on the last-mentioned shaft between the plate and said flange and in radial line with but spaced radially from the ring gear, planet gears rotatably carried on the respective bearing pins and operatively interconnecting the central gear and the ring gear, and attaching means on the head for a radial handle bar to hold it and to rotate it according to the desired use of the tool.

4. As a new article of manufacture in the hand tool class, a geared head and handle unit particularly for use accessory to stud-and-socket-type hand wrench equipment for modifying manual wrench-applied torque, said unit comprising a pair of relatively rotatable shafts adjoined in axial line and in mutual bearing relation, a sun gear fixed on an inner portion of one shaft, a cluster of individually rotatable planetary gears revolvably carried by the other shaft in meshing relation to the sun gear, a laterally open annular encompassing orbit gear meshing with the gear cluster and itself providing a laterally symmetrical outer circumferential wall of a substantially circular housing head for the unit, hub-like end cover means carried circumferentially by said head at the respective sides thereof and in marginal telescoping relation thereto and supported centrally by the shafts with the outer ends of the latter centrally accessible through said cover means, and socket-type wrench engaging formations formed directly on said accessible shaft ends.
